UNITED STATES PATENT OFFICE.

HENRY GAZAILLE AND HAMILTON F. LOW, OF MANCHESTER, NEW HAMPSHIRE; SAID LOW ASSIGNOR TO SAID GAZAILLE.

PNEUMATIC CASH SYSTEM.

SPECIFICATION forming part of Letters Patent No. 349,708, dated September 28, 1886.

Application filed December 30, 1885. Serial No. 187,142. (No model.)

To all whom it may concern:

Be it known that we, HENRY GAZAILLE, a subject of Great Britain, and HAMILTON F. Low, a citizen of the United States, both residing at Manchester, in the county of Hillsborough and State of New Hampshire, have invented certain new and useful Improvements in Pneumatic Cash Systems, of which the following is a specification.

10 Our invention relates chiefly to the terminal connections for pneumatic dispatch-tubes, which, in the present case, are adapted more especially to tubes for use in stores for the transmission of cash from the various salesmen to the cashier, and vice versa.

15 Our invention consists in the combination, with a pneumatic tube, of a transmitter of our improved construction, as hereinafter described, through which a suitable cash box or carrier is passed on its way to the cashier, and into which it is lodged when returned to a

20 salesman.

Our invention further consists in the combination, with a pneumatic tube, of our improved delivery-crane, adapted for use at the cashier's desk, and means whereby said crane shall automatically operate a signal notifying a salesman of the whereabouts of his cash.

25 Our invention finally consists in the combination, with our improved delivery-crane, of an electric or magnetic signal for communicating with a salesman.

30 We are aware that the combination of electric signals with a pneumatic dispatch-tube or cash system is not of itself novel; but we know of no arrangement of a signal operating like ours.

35 In the accompanying drawings, forming part of this specification, in which similar reference-letters indicate corresponding parts throughout the various views, Figure 1 represents a side elevation of our improved transmitter as when closed. Fig. 2 is a like view as when opened. Fig. 3 is a sectional plan of the same, taken at a point about midway from the bottom to top, having sliding cover and actuating-arm removed. Fig. 4 is a view of the open end of said transmitter. Fig. 5 is a perspective view of the sliding cover. Fig. 50 6 is a perspective view of the actuating-lever and its pivotal shaft. Fig. 7 is a side eleva-

tion of one of the delivery-crane, and Fig. 8 a front view of the same. Fig. 9 illustrates the manner of placing each plant in this improved pneumatic dispatch system, showing 55 both terminals of a tube and an air-pump connected therewith.

Our improved transmitter is designed to be fastened by means of screws to a store counter or shelf behind said counter in convenient 60 reach of a salesman.

The transmitter A, viewed at its side, rises from its base A' in a semicircle, which is hollow its entire length, thus forming a passage, A², for a suitable cash box or carrier, B. Connection is made at A³ with an air-pump, C, or a tube, D, may connect the two in case the pump must be located any distance from the transmitter, and air enters the passage A² through the slot A⁴, which is formed, as shown 70 in Fig. 4, near one end of said passage, which is otherwise closed by the base A'. The outer part of this semicircular passage A² is cut out near the closed end above mentioned, as seen in Figs. 2 and 4, for the entrance and removal 75 of the cash-carriers. This may be closed, when desired, by the air-tight cover A⁵, the peculiar construction and operation of which will be hereinafter explained. The opposite end of said semicircular passage A² is open, and may 80 be connected at A⁶ with a pneumatic dispatch-tube, E, which, in order to be out of sight and out of the way, may pass down underneath the floor and thence to the cashier's desk, where it must again rise and connect with or terminate 85 directly under the delivery-crane F.

Each plant or station should be known by a number, such as 1 2 3, &c. These must be placed in some conspicuous place upon the delivery-crane, as shown in Fig. 8, and upon 90 the cash-carriers, so as to avoid mistakes by the cashier's sending change to the wrong salesman—i. e., if the cashier's attention should be called away, and just then one of the cash-boxes should be shot from one of the delivery- 95 cranes upon his desk, he has simply to note its number, and, after making the necessary change, to place or drop it into the crane having a corresponding number, and no mistake can occur. These delivery-crane F are formed 100 of a piece of tube having a curved part, F', the inner half of which is cut away in the direc-

tion of the curve, as seen in Figs. 7 and 8, so that a cash-box may fall with less force onto the desk than if the crane were closed, except at its end, and said cash-box were discharged 5 thereat. The end of these cranes are closed, as at F². Thus, if a cash-box follows the curve F' far enough to reach the stop F², it instantly rebounds and falls to the desk with but the force of its own gravity. A base-plate, F³, 10 having rockers F⁴ formed underneath the same, (directly underneath or at either side of the vertical portion of the crane F,) projects horizontally rearward of said crane, and may be secured to the desk by a screw, F⁵, at either 15 side of the crane, as seen in Fig. 8, and to prevent the outer end of the base-plate from rising higher than need be, a screw, F⁶, is passed through the said plate near its outer end, as in Fig. 7. A wire, G, connecting a battery, P, 20 with the brass plate F⁷ or with the rockers F⁴, is provided; also, a wire, H, following the course of the pneumatic tube E from a signal-bell, p, located near the salesman's terminus 25 of said tube to a point directly under the said brass plate F⁷, and the moment the cash box or carrier strikes the curve F' while being shot out of the crane said brass plate is brought in contact with the wire H, and the signal-bell at the other end is rung. The weight of the 30 curved part F' of said crane overbalances the base-plate F³, and to regulate its vibration caused by the exit of the cash-carrier B a spring, I, bearing upon the top of said base-plate, may be provided, and adapted to induce 35 longer contact of the wire H and the brass plate F⁷.

In Fig. 9 the lines Y indicate the top of a store-counter, and the lines X the floor. J represents a wire net-work surrounding the 40 cashier's desk, this being broken out in order to show one of the delivery-cranes in position.

To return to the transmitter A, the cover A⁵ may be lined with felt or other suitable material, (see f, Fig. 5,) so that pressure may 45 render it air-tight. In order that in swinging open, this cover may rise clear of the part A, it is hung in the following manner: A hand-lever, K, is provided with a pivotal shaft, K', which passes through from one side to the 50 other of the transmitter at exactly the radial center of the semicircular part A, from the free end of which projects a stud, K², of smaller diameter and eccentric with said shaft K', the upper end of said lever K being curved, as in 55 Fig. 6, so that its hand-piece K³ may be directly over the longitudinal center of the cover A⁵. An arm, A⁷, extending downward from one side of the cover A⁵, is provided near its free end with an elongated opening, A⁸, which 60 fits onto the stud K², the position of which relative to the pivotal shaft K' is such as to cause said cover A⁵ to ride free of the transmitter A when open, as seen in Fig. 2; but when said cover is closing the opening, as in 65 Fig. 1, the said stud K² will be nearly or quite at the bottom of the opening A⁸, thus

leaving the said cover in a position to be pressed tightly upon the transmitter, which is accomplished by pressing the lever K downward until the boss K⁴ bears upon a tongue, A⁹, formed upon the top of the cover A⁵ and gradually increasing in height toward the lower end of said cover; hence the farther the lever K is moved downward the more the pressure applied to said cover A⁵. A stop, A¹⁰, may be provided against which the cover A⁵ may rest when open.

Having described our invention, what we claim as new is—

1. The combination, with a pneumatic cash-transmitting tube, an air-pump capable of inducing a current of air in either direction through said tube, and a suitable cash box or carrier, of a delivery-crane constructed substantially as herein described and located 80 near the cashier, a wire connecting with a signal-bell located near a salesman's counter, and means whereby said crane shall automatically operate said signal with the egression or reversion of the cash-box, as and in the manner explained.

2. The combined receiving box and transmitter and a vibratory delivery-crane constructed substantially as described, in combination with a pneumatic tube, an air-pump 85 capable of inducing an air-current in either direction through said tube, a suitable cash box or carrier, and an electric signal, all arranged and operating as and for the purpose set forth.

3. The transmitter connected with an air-pump, substantially as shown, combined with the sliding cover, the connecting-arm, the shaft and the operating-lever, the dispatch-tube, and the receiver, as set forth.

4. The transmitter connected with an air-pump, substantially as shown, combined with the sliding cover having the external raised tongue and the inner felt lining, the connecting-arm, the shaft and its eccentric stud, the operating-lever and its boss, the dispatch-tube, and the receiver, as set forth.

5. The curved receiving-crane having an end stop and adapted to be rocked, substantially as shown, combined with the wires forming a connection through said crane between a battery and an alarm-bell near the salesman's counter, a dispatch-tube, a receiver, and an air-pump, as set forth.

6. The open curved receiving-crane having 120 an end stop, combined with the base-plate, the rockers, the tension-spring, the electric wires connecting through the crane between a battery and an alarm-bell, the dispatch-tube, the receiver, and the air-pump, as set forth.

In testimony whereof we affix our signatures in presence of two witnesses.

HENRY GAZAILLE.
HAMILTON F. LOW.
